TEXTILE FABRIC

William Edward Holt, Jr., Philadelphia, Pa., assignor to E. W. Twitchell, Inc., Philadelphia, Pa., a corporation of Pennsylvania

Application June 7, 1954, Serial No. 30,845

Term of patent 3½ years

(Cl. D92—1)

To all whom it may concern:

Be it known that I, William Edward Holt, Jr., have invented a new, original, and ornamental Design for a Textile Fabric, of which the following is a specification, reference being had to the accompanying drawing, forming a part thereof, wherein the single figure is a face view of a piece of textile fabric showing my new design.

I claim:

The ornamental design for textile fabric, substantially as shown.
